CLAIM

The ornamental design for a portable detection device, as shown and described.

DESCRIPTION

This invention was made with Government support under Agreement No. W15QKN-18-9-1004 awarded by the ACC-NJ to the CWMD Consortium. The Government has certain rights.

FIG. 1 is a front, left, and top perspective view of a portable detection device embodying the new design;

FIG. 2 a rear, right, and bottom perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the portable detection device in which the design is embodied that form no part of the claimed design.

1 Claim, 8 Drawing Sheets
